UNITED STATES PATENT OFFICE

96,469

DESIGN FOR A HOLDER FOR FISHHOOKS

William H. Heaton, Oakland, Calif.

Application May 24, 1934, Serial No. 51,908

Term of patent 14 years

To all whom it may concern:

Be it known that I, William H. Heaton, a citizen of the United States and a resident of Oakland, in the county of Alameda and State of California, have invented a new, original, and ornamental Design for a Holder for Fishhooks, of which the following is a specification, reference being had to the accompanying drawing, forming part thereof, wherein

Figure 1 is a face view of a holder for fishhooks embodying my new design.

Figures 2 and 3 are mutually opposite edge views of the holder for fishhooks.

Figure 4 shows the holder for fishhooks opened.

I claim:—

The ornamental design for a holder for fishhooks, substantially as shown.

WILLIAM H. HEATON.
